UNITED STATES PATENT OFFICE.

SIMON COOPER, OF BROOKLYN, NEW YORK, ASSIGNOR TO THE McCALL COMPANY,
OF NEW YORK, N. Y., A CORPORATION OF NEW YORK.

FOLDING MACHINE.

Original application filed November 18, 1922, Serial No. 601,858. Divided and this application filed
February 5, 1925. Serial No. 6,945.

To all whom it may concern:

Be it known that I, SIMON COOPER, a citizen of the United States, and resident of Brooklyn, county of Kings, and State of New York, have invented certain new and useful Improvements in Folding Machines, of which the following is a specification.

This invention relates in general to folding mechanism and aims to provide mechanism particularly adapted for handling flimsy material such as tissue paper used, for example, for garment patterns.

The present invention is a division of my application Serial No. 601,858, filed November 18, 1922, wherein I have disclosed a method and apparatus for folding paper patterns. The machine described in my former application is provided with means for picking the uppermost sheet from a multiplicity of piles and feeding such sheets to an operative point where they are engaged by a wrapping arbor which is arranged to be turned through a sufficient number of revolutions to fold the sheets into a long narrow pack. After the sheets are so folded they are stripped from the arbor and the folds are creased, then the sheets are fed to another arbor which is adapted to fold the long pack in a direction to right angles to the first folds so as to wrap the sheets into a smaller or shorter compact package.

The present invention relates particularly to the means for performing the second wrapping operation, that is to say, it is directed chiefly to mechanism for receiving a long pack of previously folded sheets and for folding said sheets in another direction to make a shorter and more compact package. In handling flimsy material such as the tissue paper from which garment patterns are made, the problem of preventing the loose ends from flying about in a haphazard manner is one which must be overcome. A further problem is to overcome the tendency of the convolutions of the pack being wrapped from being separated by centrifugal force as the wrapping arbor rotates.

To overcome difficulties encountered, and to solve problems involved in the wrapping of such material, I have provided an improved tension device which effectively prevents the ends of the pack being wrapped

from whipping about in a haphazard manner and the same also overcomes the action of centrifugal force which tends to separate the different convolutions of the pack being wrapped.

The mechanism disclosed also includes means for securing a grip on a pack of folded sheets which is of such a character that it will not slip under the influence of the turning movement of the arbor, yet will permit the wrapped sheets to be readily stripped from the arbor without opening the gripping jaws. This result is secured by providing a gripping device which kinks the end of the wrapped pack as will hereinafter more fully appear.

An embodiment of the invention is illustrated in the accompanying drawings in which Fig. 1 is a vertical section through a portion of a folding machine showing the wrapping arbor and related parts;

Fig. 2 is a section on line 2—2 of Fig. 1;

Fig. 3 is a fragmentary detail viewed from the left of Fig. 1 and shows parts sectioned off on the line 3—3 thereof;

Fig. 4 is an enlarged view showing parts illustrated in the upper part of Fig. 1;

Fig. 5 is a section on line 5—5 of Fig. 4;

Fig. 6 is a somewhat diagrammatic top plan showing the relationship of the sheet wrapping arbor and the pack wrapping arbor;

Fig. 7 is an enlarged view showing details of construction of the pack wrapping arbor;

Fig. 8 is a horizontal section on line 8—8 of Fig. 7;

Fig. 9 is a similar section on line 9—9 of Fig. 7;

Fig. 10 is a plan view of the parts shown in Fig. 7, illustrating the arbor clamp in closed position and a wrapped package of sheets thereon, the figure also showing the means for exerting a gentle tension on the pack being wrapped;

Fig. 11 is a detail skeleton view showing parts which would appear in a section taken on line 11—11 of Fig. 14;

Figs. 12 and 13 are detail perspective views of different parts of the pack wrapping arbor;

Fig. 14 is a top plan view of a portion of a folding machine showing the pack wrapping arbor and related parts.

The machine disclosed in my former application of which this is a division illustrates a sheet wrapping arbor indicated diagrammatically at D, Fig. 6, which is adapted to receive a plurality of superimposed sheets and wrap them into a long narrow pack. Means are provided for stripping these sheets from the arbor D and passing them into engagement with rollers 518 and 520 which crease the folds of the pack and feed them through guides formed by spaced plates 574 and 576 into position to be engaged by the jaws of the pack wrapping arbor G forming the subject matter of the present invention. The plates forming the passage-way are supported by brackets 578 which are secured to any suitable fixed part of the framework of the machine.

The pack-wrapping arbor as shown includes a vertical spindle 580 to the lower end of which is fastened a bevel gear 582 and to the upper end of which is secured a head 584, the head being secured by flat-head screws 586 which pass through a flange 588 formed on the upper end of the spindle 580. The spindle 580 is formed with an axial bore to guide a stem 590 which is riveted to the underside of a stripper plate 592 which normally rests on the upper surface of the head 584. This stripper plate is provided with openings 594 and 596 to permit the free upward movement of the plate and also to permit the movement of the other parts to be presently described.

Rigidly secured to the head 584 and projecting upwardly through the openings 594 and 596 respectively of the stripper plate are uprights 598 and 600. The outer edges of these uprights are bevelled as at 602 and 604 so as to present a narrow edge around which the previously wrapped pack of sheets can be again wrapped or folded. The upright 598 is formed with a shoulder 606 and an inwardly extending fin 608. This upright forms the fixed jaw of the clamp for the pack-wrapping arbor. The movable jaw of the clamp comprises an upright 610 which is rigidly secured to a swinging arm 612 which is pivoted at 614 below the head 584. A spring 616 is secured at one end to the arm 612 and at the other end to a pin 613 carried on the underside of the head 584 and tends to press the jaw 610 toward the fixed jaw. The upright 610 is provided with a shoulder 618 and an inwardly extending fin 620. When the jaw is in its closed position the fin 608 of the fixed jaw and the fin 620 of the movable jaw are substantially parallel, and these members together with the upright 600 form a short narrow arbor around which the pack of pattern sheets can be wrapped so as to fold the same into a short compact package.

The arm 612 is of curved formation as

shown in plan in Fig. 9 so as to straddle the supporting bearing for the spindle 580 and thus permit of supporting the upright 610 substantially diametrically opposite the upright 600 when the clamp is in closed position. As shown in Fig. 9 the opening 594 in the stripper plate conforms in shape to the cross-section of that portion of the upright 602 which extends therethrough. Part of this opening as indicated at 595 is of arcuate shape so as to permit of slight angular movement of the upright 610 carried by the arm 612. The outer end of arm 612 carries a downwardly projecting pin 622 which is adapted to be struck at the proper time by the end 624 of a slidable rod 626 operating in fixed guides 628, shown in detail in Fig. 11. The slide-rod is normally held in its retracted position by a spring 630, one end of which is anchored to the underside thereof and the opposite end of which is secured to an eye carried by the guide as shown. An arm 632 pivoted on a shaft 634 is connected by means of a link 636 with the slide and at the proper time the lower end of the arm is struck by a pin 638 secured to a disc 639 on shaft 138 so as to swing said arm to the left, as shown in Fig. 11, and thereby cause the slide 626 to strike the pin carried by the arm 612 and thus open the movable jaw 610 of the arbor clamp. The length of the arm 632 is such that the pin 638 holds the jaw of the clamp open for a sufficient interval to permit the forward end of the folded pack to be fed between the jaws 602 and 610 of the arbor, and after the pin 638 rides off the end of the arm 632 the spring 616 will cause the jaw 610 to snap to the position shown in Fig. 10, thus securely clamping the end of the wrapped pack. It will be noticed that the shoulder portions 606 and 618 of the uprights are substantially the same width in plan so that when one jaw closes against the other they will nest together as shown in Fig. 10 and will offset or kink the forward end of the wrapped pack and therefore secure a good hold thereon. This offset grip makes it possible to wind the previously wrapped pack on this arbor without danger of the jaws losing their hold and permits the use of a comparatively light spring 616 for holding the movable jaw in closed position. It is desirable to use such a light spring because after the arbor has made a sufficient number of revolutions to wrap the pack into a package, said package must be stripped from the arbor while the spring pressure is exerted thereon. Of course means could be provided for giving a slight open movement to the movable jaw at the time the pack is stripped but this would add complication to the mechanism and the offset grip described securely holds the end of the pack during the wrapping.

operation and yet permits the same to be stripped while the spring pressure is exerted on the movable jaw.

Means are provided for periodically rotating the pack wrapping arbor G a sufficient number of revolutions to wrap the pack into a short narrow package. Locking means are also provided to hold this arbor stationary while the forward end of the pack of sheets is being transferred from the sheet-wrapping arbor D to the said pack-wrapping arbor G. And means are provided for stripping the completely wrapped package from the arbor G and feeding it into the bite of pressure rollers which will crease the folds of the package and deliver said package to a conveyor which will discharge the package from the machine.

Referring to Fig. 1 the bevel gear 582 carried by the harbor spindle 580 meshes with a similar bevel gear 640 carried by a shaft 642 mounted in bearings 644 and 646. This shaft has splined thereto a clutch member 648 which is adapted to be shifted by a shift-lever 650 so as to engage said clutch with a pin 652 carried by a sprocket 654 mounted to rotate loosely on the shaft 642. This sprocket is driven by a chain 656 from a sprocket in another section of the machine, not shown.

The shift lever 650 above referred to is pivoted at 660 to a lug secured to the bearing 476 and said lever carries a pair of rollers 662 which are adapted to engage opposite sides of a cam rib 664 formed on the periphery of a disc 666 which is secured to the shaft 486, previously referred to. This cam ridge is shaped in such a way that it causes the shift lever 650 to periodically move the clutch 648 into engagement with the pin 652 on the sprocket 654. A dwell portion of the cam permits the clutch to remain in engagement with the sprocket for a sufficient length of time to permit the pack-wrapping arbor G to make enough revolutions to completely fold the long narrow pack, stripped from the arbor D, into a short compact package. After the package has been formed, cam 664 disengages the clutch 648 and thereby stops the rotation of the arbor G. When the arbor G stops its rotation, the jaws thereof are located in approximate alignment with the axis of rotation of the sheet-winding arbor D, hence when the jaws are opened they will receive the wrapped pack of sheets which are carried forward by the transferring mechanism.

It is important that the pack-wrapping arbor G be accurately positioned and locked when it comes to rest. To these ends a locking disc 668 having a plurality of notches 670 formed therein is fixedly secured to the shaft 642. An arm 672 is loosely pivoted on a shaft 474 and is provided with a locking

finger 674 adapted to engage the notches 670 of the locking disc. The arm 672 is pulled upwardly by a spring 676 and it carries a cam roller 678 adapted to co-act with a cam plate 680 carried on the face of the cam 484, which is secured to the shaft 486. The ratio of the sprockets 658 and 654, and of the gears 640 and 582 is such that one and one-quarter revolutions of the shaft 642 will give an uneven number of revolutions to the spindle 580 so that when the arbor G comes to rest the movable jaw will always stop opposite to the guide passage formed by the plates 574 and 576. There are four notches 670 in the disc 668 and as the shaft 642 which rotates this disc makes one and one-quarter revolutions for each cycle of the machine it will be understood that the finger 674 engages a different notch during each successive cycle. It will be further understood that the cam 680 is proportioned so as to hold the finger out of engagement with the locking disc 668 for sufficient time for it to make almost one and one-quarter revolutions wheretupon the roller 678 will ride from under cam surface and the spring 676 will snap the finger against the locking disc in time to accurately position the shaft 642 after it has made the required one and one-quarter revolutions. Of course other types of locking devices such as a Geneva movement or the like could be employed to perform this function.

From the above it is clear that when the jaws 598 and 610 of the arbor G are in the open position, the rollers 518 and 520 can feed the wrapped pack of sheets from the arbor D between said jaws, and that when the slide 626 is retracted the spring 616 will cause the movable jaw 610 to grip the forward end of the wrapped pack. After this has taken place the clutch 648 will be moved into engagement with the pin 652, the locking finger 674 having previously been disengaged by the cam 680. Bevel gear 640 will now rotate gear 582 and the arbor spindle 580 through a sufficient number of revolutions to completely wrap the pack into a short package as shown in Fig. 10. After this has taken place the stripper plate 592 will be lifted by mechanism to be presently described so as to lift the package from the arbor G into the bite of a pair of opposed pressure rollers 682 and 684 shown in Figs. 1 and 4.

While the pack is being wrapped on the arbor G it is advantageous to exert a slight tension on the sides thereof to prevent centrifugal force from forcing the different convolutions of the pack outwardly. For this purpose I have provided canvas belts 686 and 688 which are secured at one end to fixed bridles 690 and 692. These bridles are fastened to upright pins 694 and 696, best shown in Fig. 6. The outer ends of the

tension belts are secured to bridles 698 and 700 and springs 702 and 704, yieldingly connect the last mentioned bridles to fixed hooks 706 and 708 carried by an upright rod 710, Fig. 14. The tension belts 686 and 688 pass through a slot 712 formed in a standard 714 which is secured to the top plate 716. This top plate bridges a space between the intermediate frame 14 and the outboard frame 12 and forms a supporting structure for the stripper mechanism and delivery mechanism to be presently described. The bearing for the pack-wrapping arbor also is carried by this supporting plate and comprises an integral hub or boss 718 through which the arbor spindle 580 extends as shown in Fig. 7.

As illustrated in Figs. 6 and 10, the belts 686 and 688 will bear on the outer surface 20 of the pack as it is being wrapped on the arbor G, it being understood that the springs 702 and 704 will yield as the arbor rotates.

For lifting the stripper plate 592 a pair of oppositely disposed arms 720 and 722 25 are mounted on a rock shaft 724 and provided at their free ends with forked plates 726 and 728 which engage the outer portion of the circular stripper plate 592. The connection is such that the stripper plate 30 can freely revolve with respect to the forked plates without exerting undue friction. In other words the plates are forked or slotted in such a way as to permit the stripper plate 592 to revolve freely.

35 After the pack has been completely wrapped into a package on the arbor G, the shaft 724 is rocked (it being understood that the arbor is locked stationary at this time by the finger 674 and disc 668) by means of an arm 730. This arm is connected to a link 732 which at its lower end is pivotally secured to a stud 734 carried by an arm 736 loosely pivoted on the shaft 774 as shown. On its free end 40 the arm 736 carries a roller 738 which rides in a cam groove 740 formed in a cam 742 keyed or otherwise secured to the shaft 486.

After the pack of sheets has been completely wrapped into a compact package the cam 742 through the connection just described causes the arms 720 and 722 to lift the plate 592 to the position shown in Figs. 4 and 5. This action partially strips the wrapped package from arbor G and moves the upper end thereof into the bite of the rollers 682 and 684. These rollers are supported by upright standards 744, the roller 682 being carried by spring pressed bearing blocks 746 which are arranged to slide on the bearing surfaces 748 formed on the standards. When the plate 592 is lifted, the tension webs 686 and 688 are flexed as shown in Figs. 4 and 5 and the springs 702 and 704 are slightly stretched 55 as will be understood.

The rollers 682 and 684 exert a pressure on the compact package and crease the folds which were made by the wrapping arbor G. These rollers then deliver the completely wrapped and creased package to the bite 70 of a pair of opposed conveyor belts 750 and 752. At their inner ends these belts are guided over rollers 754 and 756 respectively and at their outer ends said belts are trained over similar rollers 758 and 760. A slack take-up roller 762 is provided for the belt 750 and a take-up device including a rod 764 carried on a link 766 pivoted at 768 is provided to guide and take up the slack of the belt 752. The rollers 760 and 758 are located in juxtaposition to an inclined discharge chute 770 which is adapted to receive the wrapped packages from the conveyor belts and guide them by gravity to a suitable station outside of the machine.

The drive for the rollers 756 to 760 inclusive is shown in Fig. 1 and includes a sprocket 772 which is connected by means of a chain 774 with a sprocket 776 mounted on a shaft 778 carried by the standards 744. This shaft carries a spur gear 780 which meshes with a gear 782 secured to a shaft 784, this shaft being the one that supports the above-mentioned rollers 756. 85 This shaft also carries a gear 786 which meshes with a gear 788 carried on a shaft 790 which shaft supports the roller 754. This gearing is so arranged that the conveyor belts will be driven in the proper direction as indicated by the arrows in Fig. 4, to discharge the wrapped package from the machine. The drive for the pressure rollers 682 and 684 is from gear 786 through an idler 792 to gear 794 carried on the shaft 796 on which the pressure roller 684 is supported. Said gear 794 meshes with a gear 798 carried by shaft 800 which shaft supports the pressure roller 682. As indicated in Figs. 1 to 5 this gearing drives the pressure rollers in the proper direction to strip the wrapped package from the arbor G and deliver it to the conveyor belts 750 and 752. The gears 788 and 798 are offset from one another as indicated in Fig. 5 so as to avoid interference with one another as will be understood.

Though I have described with great particularity the details of the particular embodiment of the invention herein shown, it is not to be construed that I am limited thereto as changes in arrangement and various modifications may be made by those skilled in the art without departing from the invention as defined in the appended claims.

What I claim is:

1. In a folding machine, a pack-wrapping arbor comprising a rotary member having two spaced uprights secured thereto, a

clamp member pivotally secured to the rotary member and adapted to co-act with one of said uprights, means for holding the clamp closed while the arbor rotates and means for opening said clamp when the arbor is stationary.

2. In a folding machine, a pack-wrapping arbor comprising a rotary member having two diametrically opposed uprights secured thereto adapted to wrap a previously wrapped number of sheets into a flat package, a stripper plate pierced by said uprights and means engaging the peripheral portion of said plate for moving it to strip the wrapped package from the arbor.

3. A folding device including a rotary member, spaced members adapted to have a pack of sheets wrapped thereon, means pivoted to said rotary member for clamping the end of the pack to one of said members and means for exerting a gentle yielding tension on the pack being wrapped.

4. A folding device including a member having spaced extensions adapted to have a number of sheets wound flatwise thereon and flexible means anchored at both ends to fixed supports and arranged to exert a gentle yielding tension on the flat pack being wrapped around said spaced extensions.

5. A folding device including a member having spaced extensions adapted to have a number of sheets wound flatwise thereon and a flexible belt adapted to exert a gentle tension on the sheets being wound around said extensions to confine the movement of the free ends of the sheets being wrapped and to compensate for the action of centrifugal force which tends to force the different convolutions of the pack between said extensions outwardly.

6. A folding device including a rotary member having extensions adapted to have a number of sheets wound flatwise thereon and flexible belts yieldingly held between fixed supports on opposite sides of said extensions adapted to gently press against the opposite sides of the rotating pack of sheets.

7. In a folding machine a member adapted to have a pack of sheets wrapped thereon, means including a clutch and gearing for periodically rotating said member through a predetermined number of revolutions and then breaking the driving connec-

tion to permit said member to dwell and means for locking the member against rotation while the clutch is disengaged.

8. In a folding machine a member adapted to have a pack of sheets wrapped thereon, means for periodically rotating said member through a predetermined number of revolutions and then breaking the driving connection to permit said member to dwell, means for locking the member against rotation during the dwell period and means movable lengthwise of said member for stripping the wrapped pack of sheets therefrom while it is at rest.

9. In a folding machine a rotary element adapted to wrap a pack of previously wrapped or folded sheets into a smaller package, said element carrying means for kinking the end of the pack so as to exert a grip prior to the rotary movement thereof which will not slip as the pack is being wound yet will permit the same to be readily stripped endwise from said rotary element.

10. In a folding machine a rotary member having spaced extensions around which a pack of sheets are adapted to be wrapped as the member turns, and a spring pressed member arranged to kink the end of the pack of sheets and to hold it in engagement with one of said extensions.

11. In a folding machine a pack wrapping arbor adapted to wrap an elongated pack of previously folded or wrapped sheets into a shorter package, comprising a rotatable spindle having a head carrying two spaced extensions around which the pack is adapted to be wrapped and means co-acting with one of said extensions for gripping the end of the pack.

12. In a folding machine a pack wrapping arbor adapted to wrap an elongated pack of previously folded or wrapped sheets into a shorter package, comprising a rotatable spindle having a head carrying longitudinally extending members around which the pack is adapted to be wrapped and a clamp between said members adapted to kink one end of the pack and hold it in engagement with one of said members.

In witness whereof, I have hereunto signed my name.

SIMON COOPER.
